CLAIM

The ornamental design for a pet gate, as shown and described.

DESCRIPTION

FIG. 1 is a front, right, top perspective view of a pet gate in the first state, showing my new design;

FIG. 2 is a reduced scale front elevation view of the pet gate, the rear elevation view being a mirror image thereof;

FIG. 3 is a reduced scale left side view thereof;

FIG. 4 is a reduced scale right side view thereof;

FIG. 5 is a reduced scale top plan view thereof;

FIG. 6 is a reduced scale bottom view thereof;

FIG. 7 is an enlarged view of detail 7 in FIG. 1;

FIG. 8 is an enlarged view of detail 8 in FIG. 1; and,

FIG. 9 is a front, right, top perspective view of a pet gate in the second state.

The dashed broken lines in the figures illustrate portions of the pet gate that form no part of the claimed design.

The short-short-long dashed broken lines immediately adjacent to the claimed areas in the views represent the boundaries of the design and form no part of the claimed design.

The dash-dot-dash broken lines are for notating enlarged views and form no part of the claimed design.
